[57] CLAIM

The ornamental design for an attachable key light, as shown and described.

DESCRIPTION

FIG. 1 is a bottom, front, left side perspective view of an attachable key light showing my new design;

FIG. 2 is a top plan view thereof;

FIG. 3 is a front elevational view thereof;

FIG. 4 is a right side elevation view thereof;

FIG. 5 is a left side elevation view thereof;

FIG. 6 is a rear elevation view thereof; and

FIG. 7 is a bottom plan view thereof.

The key is shown in broken lines in FIG. 1 for illustrative purposes only.
